UNITED STATES PATENT OFFICE.

FRANK B. GRANGER, OF NEW YORK, N. Y., ASSIGNOR TO HALL-BORCHERT DRESS FORM COMPANY, OF NEW YORK, N. Y., A CORPORATION OF NEW JERSEY.

DRESS-FORM.

1,228,908.

Specification of Letters Patent. Patented June 5, 1917.

Application filed June 8, 1914. Serial No. 843,657.

To all whom it may concern:

Be it known that I, FRANK B. GRANGER, a citizen of the United States, residing at New York, county of New York, State of New York, have invented an Improvement 5 in Dress-Forms, of which the following description, in connection with the accompanying drawing, is a specification, like characters on the drawing representing like parts.

This invention relates to adjustable dress forms and has for its object to provide a novel construction by which the circumferential adjustment of the dress form can be greatly facilitated.

My invention is especially advantageous in securing an adjustment of the waist portion of a dress form, but it can be used in securing the circumferential adjustment of any other part of the dress form if desired. I have shown my invention as applied to a sectional dress form, that is, one in which the body of the form is made of separate sections adjustably connected together and capable of adjustment relative to each other to change the size and proportions of the form. In applying my invention to this type of dress form I provide a novel form-expanding member which will preferably be situated on the interior of the form, which is connected to the various sections of the form, and which tends automatically to force the various sections of the form outwardly thereby to expand the form and increase the circumferential measure thereof, and I also provide a size-limiting member which preferably surrounds the form and by which the expansive action of the form-expanding member is limited and the size of the form is determined. With this invention the change in the circumferential dimension of the form can be secured by merely adjusting the size-determining member, one adjustment being sufficient to accomplish the entire operation of expanding or contracting the form circumferentially.

In order to give an understanding of my invention I have illustrated herein a selected embodiment thereof which will now be described, after which the novel features will be pointed out in the appended claim.

Referring to the drawings wherein I have shown a selected embodiment of the invention, Figure 1 is a front elevation of a dress

form made in accordance with the invention;

Fig. 2 is a horizontal section on the line $x-x$, Fig. 1;

Fig. 3 is a vertical section on the line $y-y$, Fig. 1.

1 designates the body portion of a sectional dress form which may be divided into any suitable number of sections. In the illustration shown in the drawing this body portion is divided vertically in a plurality 65 of places, as indicated by the lines 2 and is also divided horizontally at or above the waist, as shown at 3, this being a more or less common way of dividing a dress form and resulting in the provision of a plurality 70 of hip sections 4 and the shoulder and neck sections 5. I have also shown each of the hip sections 4 as having hinged to the upper end thereof a waist section 6. The hinge connection between each waist section 6 and 75 the hip section 4 may be formed in any suitable way, as by means of a hinge 7.

It will be understood, of course, that the various shoulder and neck sections 5 are detachably connected to the waist sections 6, 80 and to each other, so that the waist can be lengthened or shortened by adjusting the sections 5 relative to the sections 6, and the waist of the form may be expanded or contracted circumferentially by adjusting the 85 sections 6 and 4 relative to each other.

My invention relates to a novel means for securing the circumferential adjustment of the form, and I have illustrated it as applied to the waist portion of the form for 90 expanding or contracting the latter, although it would be possible to apply the same construction to other parts of the form where circumferential adjustment is desired. In accordance with my invention I 95 provide a novel form-expanding member situated within the form and acting on the various sections thereof, which member tends normally to expand the sections outwardly, and the size of the form is controlled by a size-determining member which limits the expansive action of the form-expanding member. In the illustrated embodiment of my invention this form-expanding member is shown as a spring device 8 which is connected to each of the waist sections 6, the portion of this spring device between adjacent waist sections tend-

ing normally to spread said waist sections from each other with the result that the ultimate action of this spring device is to apply pressure to all of the waist sections tending 5 to force them outwardly. This spring device 8 is shown as a series of resilient strips 10 of spring metal, each having a general U-shape, and each secured at its ends to two of the form sections. The preferred 10 construction is one in which the two ends of any spring section 10 are connected to two adjacent form sections. The connection between the spring sections 10 and the form sections may be made in any suitable 15 way. As shown in the drawings the ends of each spring section are bent to form feet which are clamped to the form sections by clamping bolts 9.

The normal tendency of this spring member 8 is to force the form sections outwardly thereby to enlarge the form circumferentially as seen in dotted lines Fig. 2. This expansive movement of the spring 8 is controlled by a size-determining member 11 25 herein shown as a tape which encircles the form opposite the points where the spring acts on the sections 6. This tape may have any means for adjusting its length. As shown in the drawings it is provided at one 30 end with a buckle 12 for this purpose. Preferably the tape will be graduated in inches so that the exact waist measure of the form can be read at any time.

With this construction it will be readily 35 seen that if it is desired to adjust the waist of the form by increasing the circumference thereof the operator merely loosens the tape 11 and sets the buckle at the desired measurement on the tape. As the tape is 40 loosened the spring member 8 automatically

forces the waist sections 6 outwardly, the hinged construction 7 permitting this to be done without affecting the adjustment of any of the other parts. Similarly, if the waist measure of the form is to be reduced 45 in size the tape is merely taken up with the result that the waist sections are forced inwardly and the spring 8 compressed. It will be noted that the adjustment of the waist of the form is accomplished entirely 50 from the outside and without loosening any clamping bolts or nuts. Moreover, the construction of the spring device herein illustrated is exceedingly simple and cheap to manufacture, but at the same time it is 55 effective in operation.

Having described my invention, what I claim as new and desire to secure by Letters Patent is:—

The combination with a dress form, divided vertically in a plurality of places and also divided horizontally at the waist thereby to present hip sections below the waist sections above the horizontal division, of a hinge connection between each hip section 65 and the corresponding waist section, spring means connecting the waist sections and tending normally to force them outwardly thereby to expand the waist in all directions, and means acting on all of the waist 70 sections to limit the expansive movement thereof.

In testimony whereof, I have signed my name to this specification, in the presence of two subscribing witnesses.

FRANK B. GRANGER.
